UNITED STATES PATENT OFFICE.

CHARLES WELLER, OF NEWARK, NEW JERSEY.

BAR-JEWEL FASTENING.

No. 927,199.

Specification of Letters Patent.

Patented July 6, 1909.

Application filed July 1, 1908. Serial No. 441,392.

To all whom it may concern:

Be it known that I, CHARLES WELLER, a citizen of the United States, and a resident of Newark, in the county of Essex and State of New Jersey, have invented a new and Improved Ear-Jewel Fastening, of which the following is a full, clear, and exact description.

The invention relates to jewelry and its object is to provide a new and improved ear jewel fastening arranged to securely hold the jewel in place on the lobe of the ear without requiring piercing thereof, and to allow convenient manipulation of the fastening when applying or removing the jewel.

The invention consists of novel features and parts and combinations of the same, which will be more fully described herein-after and then pointed out in the claim.

A practical embodiment of the invention is represented in the accompanying drawings forming a part of this specification, in which similar characters of reference indicate corresponding parts in both views.

Figure 1 is an enlarged side elevation of the improvement, parts being in section; and Fig. 2 is a plan view of the same.

The frame or yoke A, is approximately U-shaped and carries at one end the jewel B, and a fixed cup-shaped clamping member C, disposed at the back of the jewel B and slightly out of central alignment with the same, as plainly indicated in Fig. 1. The clamping member C operates in conjunction with a slideable and turnable clamping member D, likewise made cup-shape and having a shank D', mounted to slide in a bearing E, formed on the other end of the frame or yoke A. The outer end of the shank D' is provided with a handle D'', adapted to be taken hold of by the operator, to manipulate the clamping member D, as hereinafter more fully explained. A spring F is coiled on the shank D' and extends within the bearing E, one end resting on the latter and the other on the back of the clamping member D.

On the other end of the bearing E is formed or secured an externally-extending annular bead G, formed with a slot G' for the passage of a hook arm H, attached to the member D and adapted to pass through the slot G' to engage the bead G on turning the clamping member D, so that the latter

is held locked in a withdrawn position, as plainly indicated in Figs. 1 and 2, to permit of placing the fastening into the proper position on the lobe of the ear, as indicated in Fig. 1. Now when this has been done, the operator turns the member D by manipulating the handle D'', so that the hook arm H finally comes in register with the slot G', and then the operator releases the pressure on the handle D'', to allow the spring F to push the clamping member D toward the clamping member C, thereby engaging the lobe of the ear at opposite sides by the clamping members C and D.

By having the clamping members C and D cup-shaped and the clamping member D spring-pressed, it is evident that the flesh of the lobe readily passes into the cup-shaped members C and D, at the same time the lobe is pressed on opposite sides, to securely hold the ear jewel in position on the lobe of the ear. By placing the cup-shaped members C and D out of axial alignment with the jewel B, as shown in Fig. 1, it is evident that sufficient space is had between the cup-shaped members C and D and the middle portion of the yoke A, to accommodate the lobe of the ear, as indicated in Fig. 1. When it is desired to remove the fastening, it is only necessary for the operator to pull on the handle D'', with a view to move the cup-shaped member D outward and to pass the hook arm H through the slot G', after which the user turns the handle D'', to engage the hook arm H with the bead G, thus holding the clamping member D locked in the withdrawn position and the spring F compressed.

The ear jewel fastener shown and described is very simple and durable in construction, and is composed of comparatively few parts, not liable easily to get out of order.

Having thus described my invention, I claim as new and desire to secure by Letters Patent:

An ear jewel comprising a yoke having on one arm a jewel, the other arm being provided with a bearing, a shank slideable through the bearing, said bearing having its inner end provided with an annular bead, the bead being slotted cap shaped clamping members on the first named arm and on the inner end of the shank, said clamping mem-

bers having their concave faces toward each other for the purpose set forth, the one on the shank being provided with a hook for engaging the bead, and a spring within the bearing and acting on the adjacent clamping member to move it toward the opposite member.

In testimony whereof I have signed my name to this specification in the presence of two subscribing witnesses.

CHARLES WELLER.
